UNITED STATES PATENT OFFICE.

JAMES CURRIE MORISON, OF MEMPHIS, TENNESSEE.

MEANS FOR EQUALIZING PISTON DISPLACEMENT.

1,207,429.

Specification of Letters Patent.

Patented Dec. 5, 1916.

Application filed January 4, 1916. Serial No. 70,223.

To all whom it may concern:

Be it known that I, JAMES C. MORISON, a citizen of the United States, and a resident of Memphis, in the county of Shelby and State of Tennessee, have invented a new and Improved Means for Equalizing Piston Displacement, of which the following is a full, clear, and exact description.

My invention relates to means for equalizing the piston displacement during each half engine stroke, and the object thereof is to eliminate vibration in reciprocating engines, particularly those of high speed.

With the above and other objects in view, the nature of which will more fully appear as the description proceeds, the invention consists of the novel construction, combination and arrangement of parts as herein fully described, illustrated and claimed.

20 In the accompanying drawings, forming part of the application, similar characters of reference indicate corresponding parts in all the views.

Figure 1 is a longitudinal vertical section through an engine provided with an embodiment of my invention; Fig. 2 is a transverse vertical section of the engine; Fig. 3 is a diagrammatic view of the piston displacement and the eccentric whereby the displacement is rendered uniform; Fig. 4 is a diagram illustrating the relative position of two adjacent cranks and eccentrics carried thereby; Fig. 5 is a modified structure of the means for equalizing the piston displacement; Fig. 6 is a section on the line 6—6 of Fig. 5; and Fig. 7 is a diagram showing the relative position of two adjacent cranks and the eccentrics provided thereupon.

It is a well-known fact that piston displacement is not uniform through the stroke thereof and it is dependent upon the length of the stroke and the length of the connecting rod. To obviate the difference in the displacement of the piston for each twenty degrees displacement of crank in the same stroke it is necessary to unduly increase the length of the connecting rod, which is not desirable in engines of the type used in automobiles, flying machines and motor boats, for it is impracticable, due to the desire for economy of space. Due to the variation in the piston displacement, vibration sets up in the engine, and the object of this invention is to overcome such vibration.

55 Referring to the drawings, 8 is a balanced

eccentric interposed between the connecting rod 9 and the corresponding crank 10 of the crank shaft 11. The eccentric is provided with a pinion 12 meshing in an interior gear 13 mounted within and secured to the crank 60 casing 14. The ratio between the gears 12 and 13 is such that the eccentric will revolve twice during a single revolution of the crank, as shown in Fig. 3.

It will be noted from Fig. 3 that, as the 65 crank 10 moves through an angle of ninety degrees from A to B, the eccentric 8 will move through an angle of one hundred and eighty degrees, thus increasing the distance between the crank and piston to compensate 70 for the displacement of the connecting rod from the axis of the cylinder due to the displacement of the crank 10. As the crank is displaced from B to C through an additional angle of ninety degrees, the eccentric 75 8 is revolved through an angle of one hundred and eighty degrees, thus shortening the distance between the crank and piston as the connecting rod moves toward the axis of 80 the cylinder. The movement of the connecting rod from C to A is similar to what has been stated from A to C. It is self-evident that the eccentric 8 is of a proper size to obtain the desired compensation to eliminate 85 the inequality of displacement of a piston 15 during each half of its stroke.

In Diagram 4, D is the position of the eccentric of one of the engine cylinders, and E is the position of the eccentric of an adjacent cylinder of the engine. The angle formed by the connecting rod with the corresponding axis of its cylinder will be d and e . D' and E' illustrate the relative position of the eccentrics after the crank shaft has revolved through ninety degrees, the change 95 in angles being represented by d' and e' . From this diagram it will be seen that the angle d is larger than the angle e at a certain position of the crank shaft, and at a 100 different position of the crank shaft the angle d' is less than the angle e' . Consequently, the speeds of two adjacent pistons are not equal through the strokes thereof. However, the difference in the rate of speeds 105 of the two adjacent pistons is so slight that the vibration which may result will be practically *nil*.

In cases where it is desired to obtain a perfect equality of speed between two adjacent pistons, the adjacent eccentrics of the 110

shaft are caused to rotate in the opposite direction, and such arrangement is illustrated in the structure disclosed in Figs. 5 to 7 inclusive. The Diagram 7 shows such an arrangement. F indicates the position of an eccentric of one cylinder, while G indicates the position of the eccentric of the adjacent cylinder of the engine. It will be noted that the two eccentrics revolve in opposite directions, F' and G' indicating the position of the said eccentrics after the crank shaft has revolved through an angle of ninety degrees. The angle f formed by the cylinder axis with the connecting rod 10 operating with the eccentric F is equal to the angle g , and the angle f' also equals the angle g' at a different position of the eccentrics. Therefore, with such an arrangement the speeds of the two adjacent pistons at 15 any point are equal, and thus a perfect balance between any two adjacent pistons is obtained. To reverse the direction of an eccentric 8' the pinion 12' associated therewith is not meshed to the stationary interior gear 13', but an idler 16 is interposed between the pinion and the stationary gear, which idler is carried by the crank shaft 11'. 20

From the foregoing description taken in connection with the accompanying drawings, the advantages of the construction and method of operation will be readily understood by those skilled in the art to which the invention appertains, and while I have described the principle of operation, together 25 with the apparatus which I now consider to be the best embodiment thereof, I desire to have it understood that the apparatus shown is merely illustrative and that such changes may be made when desired as fall within 30 the scope of the appended claims.

Having thus described my invention, I claim as new and desire to secure by Letters Patent:

1. Means for equalizing piston displacement in engines, comprising, in combina- 40

tion, a piston, a crank shaft, and an oscillating connecting rod connecting the piston to the shaft, with eccentric means interposed between the crank and rod to compensate for the variation in distance between the 50 crank shaft and piston by the oscillation of the rod.

2. Means for equalizing piston displacement in engines, comprising, in combination, a piston, a crank shaft, and an oscillating 55 connecting rod from the shaft to the piston, with an eccentric interposed between the shaft and rod, and means for revolving the eccentric through an angle twice that of the shaft.

3. Means for equalizing piston displacement in engines, comprising, in combination, a piston, a crank shaft, an oscillating connecting rod from the shaft to the piston, with an eccentric interposed between the 60 shaft and rod, a pinion revoluble with said eccentric, and a stationary gear meshing with said pinion, whereby said eccentric is caused to revolve during the revolution of the shaft, the ratio of said pinion and gear 65 being such that said eccentric is caused to revolve twice during a single revolution of the shaft.

4. Means for equalizing piston displacement in engines, comprising, in combination, 70 a crank shaft, oscillating connecting rods from the shaft, pistons associated with said connecting rods, with an eccentric interposed between each crank of the shaft and the connecting rod, and means for revolving the eccentrics of the adjacent cranks in opposite directions and through two revolutions for each revolution of the crank shaft.

In testimony whereof I have signed my name to this specification in the presence of 80 two subscribing witnesses.

JAMES CURRIE MORISON.
